SEWING MACHINE FEEDING MECHANISM

Andrew B. Clayton, Union, N. J., assignor to
The Singer Manufacturing Company, Elizabeth, N. J., a corporation of New Jersey

Application October 29, 1931. Serial No. 571,704

3 Claims. (Cl. 112—215)

This invention relates to sewing machines, more particularly of the cylinder-bed type, and has for an object to provide such a machine with a feeding mechanism, the feed-dog of which has a "parallel motion" or, in other words, moves so that its work-engaging surface is substantially parallel to the throat-plate at all times during its rising-and-falling and feeding-and-return movements. I believe I am the first to provide a cylinder-bed sewing machine with such a feed-motion arranged to feed the work in a direction across or transversely of the cylinder-bed.

A feature of the invention is its compactness and peculiarly efficient adaptability to the requirements of a cylinder-bed chain-stitch sewing machine wherein space is at a premium. Another feature of the invention is its sturdiness and ability to handle heavy work without undue strain on the parts.

With the above and other objects in view, as will hereinafter appear, the invention comprises the devices, combinations and arrangements of parts hereinafter set forth and illustrated in the accompanying drawings of a preferred embodiment of the invention from which the several features of the invention and the advantages attained thereby will be readily understood by those skilled in the art.

Fig. 1 is an end view of the cylinder-bed of a sewing machine showing my improved feeding mechanism incorporated therein. Fig. 2 is a top plan view of the feeding mechanism. Fig. 3 is a view substantially on the line 3—3, Fig. 2, with the feed-dog and its carrier-bar removed. Fig. 4 is a section on the line 4—4, Fig. 2. Fig. 5 is a section on the line 5—5, Fig. 2. Fig. 6 is a perspective view of the feed-bar. Fig. 7 is a perspective view of the feed-rocker, and Fig. 8 is a perspective view of the feed-rocker supporting and lifting means which may be called a feed-lift rocker.

1 represents the hollow cylinder-bed of a sewing machine within and lengthwise of which is the main-shaft 2. The throat-plate is shown at 3 and the feed-dog at 4. The feed-dog 4 has the usual shank 4' which is seated in the groove 5 in the feed-bar 6 clamped to the pin 7 which is journaled in the upstanding ears 8, 8 of the feed-rocker 9. The feed-bar has an offset forked arm 10 which embraces the follower block 11 on the feed-lift eccentric 12 on the main-shaft 2.

The feed-rocker 9 is fulcrumed on the supporting pin 13 of the feed-lift rocker including the spaced arms 14 which carry the pin 13 and are fixed to the rock-shaft 15 journaled in the lower

rear corner of the cylinder-bed 1 in bearings 16, 16. Adjustably clamped by screws 17' to the rock-shaft 15 is a vertical arm 17 which is connected by a pitman 18 to a second feed-lift eccentric 19 on the main-shaft 2. The feed-lift eccentrics 12 and 19 are timed to lift the front and rear ends of the feed-bar 6 substantially simultaneously and to substantially the same extent, thereby maintaining the feed-dog 4 in a horizontal position at all times with its teeth parallel to the throat-plate 3.

The feed-rocker 9 has two ears 20, 20 affording a long bearing for the pin 21 to which pin is fixed the pitman 22 embracing the adjustable feed-advancing eccentric 23 on the main-shaft. 70 The collar 24 fixed to the pin 21 between the ears 20, 20, holds the pin 21 against endwise movement.

It will be observed that the feed-rocker 9, which supports and lifts the rear end of the feed-bar 6, is of the maximum vertical dimension allowed by the space within the cylinder-bed. This provision minimizes and renders negligible the vertical component of motion of the rear end of the feed-bar about the pin 13 as a center. 80 A substantially true parallel motion of the feed-dog is thus more easily attained.

By loosening the set-screws 17' which clamp the arm 17 to the feed-lift rock-shaft 15, the feed-rocker 9 may be raised or lowered to adjust 85 the plane of the feed-dog teeth to the desired parallel relation to the throat-plate 3. By this same adjustment the feed-dog may of course be tilted either forwardly or rearwardly as may be desired in certain special sewing operations where 90 a fulling or stretching action is required.

It is also to be noted that the present feed-mechanism is entirely clear of the space below and in front of the main-shaft which is occupied by the looper-mechanism shown in my copending application Serial No. 571,703, filed herewith.

Having thus set forth the nature of the invention, what I claim herein is:—

1. In feeding mechanism for sewing machines, a main-shaft having three eccentrics thereon two of which are feed-lift eccentrics and one of which is a feed-advance eccentric, a feed-dog, a feed-bar carrying said feed-dog and supported at its front end by one of said feed-lift eccentrics, a vertically disposed feed-rocker supporting the rear end of said feed-bar, a feed-lift rocker fulcrumed in rear of said feed-rocker and pivotally carrying the latter, said feed-lift rocker including an upstanding arm, a horizontal pitman connection between said upstanding arm and the

other of said feed-lift eccentrics, and a horizontal pitman directly connecting said feed-rocker and said feed-advance eccentric.

2. Feeding mechanism for sewing machines comprising a main-shaft having two feed-lift eccentrics and one feed-advance eccentric thereon, a feed-bar supported at its front end by one of said feed-lift eccentrics, a feed-rocker arranged vertically in rear of the main-shaft and 10 pivotally supporting the rear end of said feed-bar at a point above the level of said main-shaft, a feed-lift rocker pivotally carrying said feed-rocker, a pitman connected at one end to said feed-advance eccentric and at its other end connected directly to said feed-rocker at a point between the feed-bar and the feed-lift rocker, and a horizontal pitman connection between the feed-lift rocker and the other feed-lift eccentric.

3. A sewing machine having a frame including a work-supporting bed in the form of a hollow horizontal arm, a throat-plate, a shaft journaled within and lengthwise of said hollow horizontal arm, a feed-dog arranged to feed the work transversely of the free end of said arm, a feed-bar disposed transversely of and within the free end of said arm, a feed-eccentric on said shaft and connections for imparting feed-and-return movements to said feed-bar, and a pair of feed-lift eccentrics on said shaft and independent connections for imparting synchronized feed-lift movements to said feed-bar at two spaced points in the length of the feed-bar, one of said connections including a feed-lift rock-shaft journaled within and lengthwise of said arm.

ANDREW B. CLAYTON.
